STAND FOR MUSICAL INSTRUMENTS

Albion Slayton Lang, Roslindale, Mass.

Application February 7, 1935, Serial No. 5,489

4 Claims. (Cl. 248—167)

This invention relates to stands for musical instruments and particularly to stands or supports designed to hold a saxophone or like instrument and a clarinet, oboe, English horn, trumpet, flute or other similar instruments having an open end and adapted to be supported on an upright peg.

Many orchestras are also organized so that one or more of the players are expected to play both a saxophone and some other instrument such as a clarinet, or a flute, and the stand or support to which this invention relates is one adapted to support both a saxophone and one or more instruments such as mentioned above so that the player can readily select from the stand the instrument which he is called on to play at anytime.

One of the objects of my invention is to provide a musical instrument stand which is made in units, each of which units is adapted to support a saxophone or similar instrument and one or more instruments such as a clarinet, flute, oboe, etc., such units being so constructed that two or more units can be readily coupled together to produce a multi-unit stand which will support a plurality of instruments of the saxophone type and also a plurality of other instruments such as the clarinet, flute, oboe, etc.

A further object of the invention is to provide a musical instrument stand of this construction which is made of separate elements detachably secured together so that the stand may be readily taken down and packed in the instrument case for transportation.

Other objects of the invention are to improve musical instrument stands in various particulars hereinafter set forth.

In the drawings wherein I have illustrated one embodiment of my invention:

Fig. 1 shows a single unit adapted to support a saxophone and having one or more pegs to support a clarinet, oboe, flute, trumpet or similar instrument.

Fig. 2 is a view showing one way in which two units may be coupled together to make a duplex unit adapted to support two saxophones and having two pegs for supporting a clarinet, flute or other instrument of the type which can be supported on a peg.

Fig. 3 is a perspective view showing a different way in which the two units may be coupled together to produce a duplex stand.

Fig. 4 is an enlarged section on the line 4—4 of Fig. 1.

Fig. 5 is a fragmentary perspective view show-

ing the way in which the saxophone-holding yokes are attached to the supporting stand or upright.

Fig. 6 is a fragmentary perspective view of the foot portion of the saxophone-supporting element.

Fig. 7 is a perspective view of one of the bars forming part of the support.

Fig. 8 is a fragmentary perspective view illustrating the means for attaching the rest 15 to the upright.

Fig. 9 is a fragmentary perspective view of the post for supporting a clarinet or like instrument.

Fig. 10 is a perspective view of the base member.

As stated above a musical instrument stand embodying my invention is made in units which may be used singly or may be coupled together to produce a duplex or multiplex stand. Each unit comprises a base member 1 which may be of wood, metal or any other suitable material, a cross member 2 in the form of a bar which extends transversely of the base member 1 and is superposed thereon and which serves to provide a wide base for the stand and also to support instrument-supporting pegs 7, and a saxophone-supporting element 3 which is detachably secured to the base 1 and is designed to support a saxophone.

The posts or pegs 7 which are designed to support a clarinet, oboe, flute or any other instrument having an open end which can be placed over the peg, are detachably secured to the cross member 2. Each peg is provided in its bottom with a depending screw-threaded stud 8 which is adapted to extend through one of the slots 5, 6 and to receive a clamping nut 9 by which the peg or post 7 is detachably secured to the cross member.

The saxophone-supporting member 3 comprises the upright or standard 10 which is formed at its lower end with two oppositely directed foot portions 11, 12 the foot portion 11 having a slot 13 formed in its end which extends longitudinally thereof, and the foot portion 12 having a slot 14 adjacent its end which extends transversely thereof. The upper part of the saxophone-supporting element is preferably bent backwardly and at the upper extremity thereof is a U-shaped yoke member 15 adapted to receive the bell end of the saxophone. The saxophone-supporting member is also provided intermediate of its ends with a U-shaped rest 16 against which the body of the saxophone rests. The yoke member 15 is detachably clamped to the standard 3 as shown in Fig. 5. The upper end of the standard 3 is pro-

- vided with a slot 17 and the yoke 15 has a screw-threaded stud 18 extending therefrom which is adapted to enter said slot, the yoke 15 being clamped to the standard 3 by the clamping nut 19.
- 5 The clamping means for the yoke member 15 is preferably provided with two interengaging portions which co-operate to positively prevent the yoke from turning on the supporting member 3. In the construction shown the stud 18 has the flat sided portion 38 of a size to fit between the walls of the slot 17. The flat sides 38 and the walls of the slot constitute the interengaging portions which positively prevent turning movement of the rest 15 on the supporting member 3 when 10 the clamping nut 19 is tightened up. In this way the rest 15 will always be held firmly in its correct position. By loosening the nut 19 sufficiently to withdraw the flat portion of the stud from the slot it is possible to turn the rest 15 into a position in line with the stem 3 and then to tighten it again in such position when the instrument is taken down for packing or shipment. A similar construction may be employed for securing the rest 16 to the standard 3.
- 15 The base member 1 carries two clamping bolts 20, 23 which may conveniently be permanently anchored in said base members. For this purpose each clamping bolt is shown as inserted through the base member from the under side and 20 as having an anchoring nut 31 screw-threaded thereto, said nut preferably being received in a recess formed in the base member so that the top of the nut will not project above the upper surface of the base member.
- 25 In assembling the elements to make a single unit as shown in Fig. 1 the cross member 2 is placed in a position overlying the base 1 and with the central slot 5 thereof receiving the clamping stud 20. The saxophone-supporting member 10 is then placed in position with the foot 11 resting on the base member and the slot 13 therein receiving the clamping bolt 23 and with the foot 12 resting on the cross member 2 and the slot 14 thereof receiving the clamping bolt 20. The 30 clamping nut 22 carried by the clamping bolt 20 and also the clamping nut 25 carried by the bolt 23 are then tightened, the tightening of these nuts serving to clamp the feet 11 and 12 and the cross member 2 firmly to the base member 1.
- 35 A post or peg 7 may then be attached to one or both ends of the cross members by entering the screw-threaded stud 8 of the peg into the slot 6 and then tightening the clamping nut 9. Since the pegs 7 are detachable from the cross member 50 it is possible to use a peg 7 such as shown in Fig. 1 which is adapted to enter the bell end of a clarinet, oboe, trumpet or the like or to use a peg such as shown at 1a which is designed to support a flute. A unit constructed as above is 55 adapted to support one saxophone and one or two other instruments such as a clarinet, oboe, trumpet, flute, etc. depending upon whether the cross member 1 carries one or two of the instrument supporting pegs and the character of such pegs.
- 60 If it is desired that the stand should support two saxophones then two of the units such as shown in Fig. 1 may be coupled together to produce a duplex stand such as shown in Fig. 2. This is done by taking the two units and placing them with their base members in parallel relation but spaced apart and with one end of the cross member of each unit in position to be clamped to the base member of the other unit.
- 65 In Fig. 2 the base member of the second unit 70 is shown at 1a, and the cross member of said second unit is shown at 2a and the saxophone support of said second unit is shown at 3a. The end of the cross member 2 of the first unit overlies the base member 1a of the second unit and extends underneath the foot 12a of the saxophone support 3a of said second unit. The clamping bolt 20a of said second unit extends through the slot 6 at the end of the cross member 2 and also through the slot in the foot 12a of the second unit.
- 75 The cross member 2a of the second unit is placed on the base 1a of said unit with the central slot thereof engaging the clamping bolt 23a of said second unit, and the outer end of the cross member 2a overlies the base 1 of the first unit and the clamping bolt 23 of the first unit extends through the slot 6 at the end of said cross member 2a. When the nuts 22a and 25a are tightened the two units will be firmly clamped together as shown in Fig. 2. The outer or projecting ends of the cross members 2 and 2a may have instrument-supporting pegs secured thereto as shown, either one having a cone shape shown at 7 and adapted to receive a clarinet or an instrument having a similar bell end, or one having a cylindrical shape as shown at 1a and constructed to enter the open end of and support a flute. The duplex stand shown in Fig. 2 will thus support two saxophones and two other musical instruments. Another way in which the two units may be coupled together to make a duplex unit is shown in Fig. 3. In this embodiment the two base members 1 and 1a of the two units are spaced apart the full length of the cross members 2, 2a and the ends of the cross members are clamped to the base members by the clamping bolts 20, 23, 20a, 23a. In this embodiment also the two pegs 7 are detachably secured to the central portions of the two cross members 2, 2a by inserting the screw-threaded studs of said posts 7 into the central slots 5 and tightening the corresponding clamping nuts 9.
- 80 In this embodiment of the invention the clarinets will be supported between the saxophones, while in the arrangement shown in Fig. 2 the saxophones are shown supported between the clarinets.
- 85 If it is desired to provide a stand for supporting more than two saxophones, then three or more units may be coupled together to produce a multiple unit stand of any desired size.
- 90 The clarinet-supporting posts 7 are shown as formed with a bottom flange on which the clarinet rests. This flange may be in the form of a disk 30 through which the screw-threaded stem 8 extends and which is somewhat larger than the lower end of the posts 7.
- 95 I claim:
1. A stand for musical instruments presenting a stand unit having a supporting base including a base member to rest on the floor and having two studs projecting upwardly therefrom and a cross member superposed on the base member and extending transversely thereof, said cross member having a slot to receive one of said studs and also having downwardly bent ends constituting supporting feet, a saxophone support having two oppositely directed foot portions, each having a slot to receive one of said threaded studs, clamping nuts on said studs, and each end of the cross member having a slot adapted to receive a threaded stud from an instrument-supporting peg, thereby forming a single unit, or to receive the threaded stud of a base member of a second

- similar unit, thereby forming a duplex or multiple unit stand.
2. A stand for musical instruments presenting a stand unit having a supporting base which comprises a base member adapted to rest on the floor and having a threaded stud projecting upwardly therefrom, a cross member superposed on the base member and extending transversely thereof, said cross member having a slot to receive said stud and having downturned ends to form supporting feet, a saxophone support having a foot portion provided with a slot to receive said stud, a clamping nut carried by the stud for clamping the foot portion and cross member to the base member, each end of said cross member having a slot to receive a threaded stud from an instrument-supporting device or to receive the threaded stud of a second similar unit thereby forming a duplex or multiple unit stand.
- 20 3. A musical instrument stand presenting a stand unit having a base member to rest on the floor, a cross member superposed on the base member and extending transversely thereof, said

cross member having downturned ends to form supporting feet, means for detachably securing an instrument support and the cross member to the base member, instrument-supporting means secured to one end of the cross member, the other end of the cross member having provision for detachably engaging the instrument-securing means carried by the base member of a second similar unit, thereby forming a duplex or two-unit stand.

4. A stand for musical instruments having a supporting base, a saxophone support secured to said base and rising therefrom, said saxophone support comprising a stem having a slot at its upper end a U-shaped rest to receive the bell end of the saxophone, said U-shaped rest having a threaded stud extending therefrom adapted to be entered into said slot, a clamping nut screw-threaded to said stud for clamping the rest to the stem, the portion of the stud received in the slot having flat faces to engage the opposite walls of the slot.

ALBION SLAYTON LANG.
